UNITED STATES PATENT OFFICE.

EINAR THORESEN, OF CLEVELAND, OHIO.

LEAD-SHARPENING DEVICE.

Application filed August 3, 1925. Serial No. 47,912.

To all whom it may concern:

Be it known that I, EINAR THORESEN, a subject of the Kingdom of Norway, residing at Cleveland, in the county of Cuyahoga and State of Ohio, have invented new and useful Improvements in Lead-Sharpener Devices, of which the following is a specification.

This invention relates to lead sharpening devices designed for pointing the leads of pencils, an object being to provide a device of this character which is especially adapted for pointing compass leads.

Another object of the invention is the provision of a lead sharpening device by means of which compasses or pencil leads may be sharpened either upon one side of the point, or the other, or upon both sides.

With the above and other objects in view, the invention further includes the following novel features and details of construction, to be hereinafter more fully described illustrated in the accompanying drawings and pointed out in the appended claims.

25 In the drawings:—

Figure 1 is a sectional view illustrating the use of the invention.

Figure 2 is a top plan view of the device.

30 Figure 3 is a fragmentary elevation showing a portion of one of the inclined abrasive surfaces.

Figure 4 is an elevation partly broken away showing a slightly different form of the invention.

35 Referring to the drawings in detail wherein like characters of reference denote corresponding parts, the reference character 10 indicates a cup-like receptacle which is preferably formed of thin sheet metal and which 40 is designed to hold a plurality of annular concentrically arranged sharpening elements 11, the latter extending around a centering member 12.

45 The sharpening elements may be formed of any suitable material, such as hardened steel, carborundum and so forth, while the centering element is preferably formed of soft metal and is provided with a central indentation to receive the needle point of one leg 13 of a compass, the other leg 14 carrying a lead 15. The lead 15 is usually sharpened by flattening one or both sides and to facilitate this, the elements 11 are provided with beveled or inclined abrasive surfaces 16, these surfaces being knurled or serrated when the sharpening elements are of hard-

ened steel. To provide for sharpening the lead upon both sides, the outer and intermediate sharpening elements have their abrasive surfaces relatively inclined so as to provide a substantially V-shaped groove 17 whose opposed walls form the sharpening surfaces so that by arranging the compass in the position shown in Figure 1 and moving said compass in a rotary direction, the lead 15 will be sharpened as indicated. The innermost sharpening element 11 and the intermediate sharpening element have their opposed abrasive surfaces spaced by means of a spacing ring 18, so that by contact with the surface *a*, the outer side of the lead will be beveled while engagement of the lead with the surface *b* will bevel the inside of the lead. The sides of the receptacle 10 are preferably extended above the upper faces 75 of the sharpening elements as indicated at 19.

In Figure 4, a single annular sharpening element 20 is provided within a casing 10, the element being secured in place by indenting a portion of the casing so as to engage 80 the walls of the socket 21 provided in the sharpening element 20, any desired number of these indented portions and sockets being provided. A press fit is thus made to hold the sharpening element in place.

85 Positioned concentrically within the annular sharpening element 20 is a combined centering element and guide member 22 whose outer tapered edge 23 is rounded and spaced from the abrasive surface 24 of the sharpening element 20, so that the lead may 90 rest upon this tapered rounded edge 23 and engage with the abrasive surface to bevel one side of the lead. The member 22 is held in place by a press fit with the casing 95 10 as indicated at 25. A centering notch 26 receives the needle point of the compass.

If desired, this form of the invention as well as that illustrated in Figures 1 and 2 may be provided with a cover 27 and a felt 100 or other compressible ring 28 may be interposed between this cover and the members 20 and 22. The space provided between the sharpening element 20 and the under inclined face of the member 22 may receive 105 the dust from the lead.

The invention is susceptible of various changes in its form, proportions and minor details of construction and the right is here reserved to make such changes as properly fall within the scope of the appended 110 claims.

Having described the invention what is claimed is:—

- 5 1. A lead sharpening device for compasses comprising a sharpening element having an inclined abrasive surface, means to guide the lead along said surface and means to support one leg of the compass.
- 10 2. A lead sharpening device for compasses comprising a sharpening element having a circular abrasive surface and means located concentric of the abrasive surface to provide a supporting center for one leg of the compass.
- 15 3. A lead sharpening device for compasses comprising a supporting center for one leg of a compass and concentrically arranged oppositely inclined abrasive surfaces encircling said supporting center.
4. A lead sharpening device for compasses

comprising a supporting center for one leg of a compass, a plurality of annular sharpening elements arranged concentrically of the supporting center, oppositely inclined abrasive surfaces for said elements and means to hold the elements in position.

25 5. A lead sharpening device for compasses comprising a supporting center for one leg of a compass, a plurality of annular sharpening elements arranged concentrically of the supporting center, oppositely inclined abrasive surfaces for said elements and a substantially cup shaped receptacle receiving said elements and providing an annular flange extending above the upper face of said elements.

30 35 In testimony whereof I affix my signature.

EINAR THORESEN.
